WALTER S. FISHER, OF TOLEDO, OHIO, ASSIGNOR TO THE WILLYS-OVERLAND COMPANY,
OF TOLEDO, OHIO, A CORPORATION OF OHIO

HEAD COOLING MEANS

Application filed December 26, 1929. Serial No. 416,452.

This invention relates to internal combustion engines and more particularly to a means and method for cooling the cylinder heads of sleeve valve engines.

One of the objects of the invention is to provide a means for directing water toward the hottest portions of the engine head.

Another object of the invention is to provide a forced circulation of water in the depending heads of Knight engines.

Another object of the invention is to provide a deflector which may be readily installed in existing engines and which will direct a water flow toward the lower portion of the head.

Other objects will appear from the description to follow and from an examination of the physical embodiment which may be preferred, that I have illustrated in the accompanying drawing, in which

Figure I is a top plan view, partly in section, of a portion of a sleeve-valve engine embodying the improved cooling system.

Fig. II is a sectional view taken along lines II—II of Figure I.

The engine selected to illustrate this invention is the well known Knight engine type, 10 being the cylinder in which reciprocate sleeves 12 and 14 and in which is a depending head 16 bolted to the cylinder by bolts 18.

The head inner wall 20 and outer wall 22 are cylindrical and concentric with the bore of the cylinder 10. The inner wall 20 projects up through the water cover 24, which is held

in place by nut 26 that presses the cover 24 downwardly upon the cylinder 10, a rubber gasket 28 being interposed between the cylinder cover and the cylinder, and a rubber gasket 30 being interposed be-

tween the nut 26 and the cover 24. The inner wall 20 is in the form of a tubular extension and provides a space for a spark plug (not shown) which may be screwed into the threaded portion 32 at the bottom of the head.

Between the walls 20 and 22 is an annular water space 34 which communicates with the main water space enclosed by cover 24, and which in turn is in communication with the cylinder jacket 36.

The construction described so far is old

in sleeve valve engines which type of engine has some limitations in regard to cooling of the cylinder head. The water space 34 as ordinarily constructed has no separate inlet and outlet, and the circulation therein is somewhat sluggish. In the present invention the circulation is accelerated by providing a tubular partition, or deflector, 38 that surrounds the inner wall 20 and divides the space 34 vertically into two passages. The deflector 38 projects downwardly to a point adjacent the bottom of space 34 and is provided at its upper end with an in-turned flange 40 which closely surrounds the wall 20 and closes the upper portion of the inner passageway. The deflector preferably is formed in a separate piece and is secured to the head by means of a set screw 41. Immediately below the flange 40 is a threaded opening 42 in which is screwed a pipe 44 which projects through the cover 24 and communicates with a manifold 46 which supplies water in a similar manner to other deflectors placed in the remaining cylinders of the engine. A gasket 47 surrounds pipe 44 where it enters the cover 24 and maintains a water tight joint at this point. Water is supplied to manifold 46 through pipe 48 from any desirable source such as the engine water pump (not shown). I prefer to project the pipe 44 through the cover of the engine as shown in the form herein illustrated but, if desired, this pipe may be connected with the cylinder wall jacket 36 or any other source of water pressure.

During the operation of the engine the space 34 is entirely filled with water which will circulate slightly due to the difference in density between the heated water at the lower portion of the head and that at the upper portion within the space defined by the cover 24. In addition to this inherent circulation water will be directed by pipe 44 through the deflector 40 into the annular space surrounding the projection 20, from thence downwardly, and impinging upon the lower portion 50 of the head which is in direct contact with the heated gases of the engine. The water will be directed beneath the lower end of the tubular deflector 40 and

will rise on the outside of the deflector to the water space beneath the cover 24 where it may be disposed of in accordance with the usual manner of water cooling internal combustion engines.

While I have shown and described somewhat in detail a preferred form of my invention, it is understood that this showing and description is illustrative only and I do not regard my invention as so limited, except wherein I have included such limitations within the terms of the following claims.

I claim:

15. 1. In an internal combustion engine, the combination of a depending cylinder head having an upstanding inner wall, said wall forming with the head outer wall an annular cooling space, a tubular member surrounding said inner wall in spaced relation thereto, said tubular member having its lower end open and in communication with the cooling space, and means for introducing water between said member and the inner 25 wall of the head.

20. 2. In an internal combustion engine, the combination of a depending head having an annular water space therein, a tubular member secured to said head vertically dividing said water space, said tubular member having its bottom end open, and means forming an opening through said tubular member adjacent the upper end thereof.

35. 3. In an internal combustion engine, the combination of a depending head having an annular water space, a tubular partition extending downwardly within said space in spaced relation to both inner and outer walls thereof whereby said space is divided into 40 annular passageways, means forming communication between said passageways adjacent the bottom of the annular space, and means for introducing water within one of said passage ways.

45. 4. In an internal combustion engine the combination of a depending cylinder head having inner and outer walls forming an annular water space, a vertical tubular partition, within said space terminating adjacent the bottom thereof, means for introducing water on one side of said partition, and means for causing the water on one side of the partition to flow downwardly toward the bottom of said annular space.

55. 5. In an internal combustion engine, the combination of a depending cylinder head having inner and outer tubular walls forming an annular water space therebetween, a tubular partition intermediate said walls in spaced relation thereto, means forming a passageway between opposite sides of the partition at the lower end thereof, means forming a passageway through the partition at the upper end thereof, and means for causing water to flow through one passageway

and along one side of the partition in one direction, and along the other side of the partition in the opposite direction.

6. In an internal combustion engine the combination of a depending cylinder head 70 having inner and outer walls forming an annular water space within the head, a tubular deflector forming a vertical partition within said annular space, said deflector having an inturned flange at its upper end in contact with the inner walls of the head, the lower portion of said deflector being spaced from both the inner and outer walls of the head, means forming a communication between opposite sides of said deflector adjacent the bottom of the space, and means forming a water conduit in communication with the interior of said deflector below the inturned flange.

7. In an internal combustion engine the 85 combination of a depending cylinder head having concentric inner and outer walls forming an annular water space, a tubular deflector surrounding the inner walls in spaced relation thereto and projecting down 90 within the space adjacent the bottom thereof, means forming a closure between the deflector and the inner wall, means forming a water conduit to the space between the deflector and inner wall, and means forming a passage between opposite sides of said deflector adjacent the bottom of the water space.

8. In an internal combustion engine, the combination of a cylinder having a water jacket, a cylinder head closing the upper end 100 of said cylinder, a cover over said cylinder and head enclosing a water space in communication with the water jacket and the upper surfaces of the head, said head having a hollow extension thereon projecting upwardly through said cover, a deflector encircling said extension in spaced relation thereto, and means for producing water flow between said deflector and extension.

9. In an internal combustion engine, the 110 combination of a cylinder having a water jacket, a cylinder head closing the upper end of said cylinder, a cover over said cylinder and head enclosing a water space in communication with the water jacket, said head having outer walls and a tubular extension projecting upwardly through said cover, said extension forming with the side walls an annular water space, a tubular deflector encircling said extension in spaced 115 relation thereto, means forming a closure for the upper end of the space between the deflector and extension, said deflector having its lower end open, and means for directing water through the deflector adjacent the upper end thereof.

10. In an internal combustion engine, the combination of a cylinder having a water jacket, a cylinder head closing the upper end 120 of said cylinder, a cover over said cylinder

and head enclosing a water space in communication with the water jacket, said head having outer walls and a tubular extension projecting upwardly through said cover, said extension forming with the side walls an annular water space, a tubular deflector encircling said extension in spaced relation thereto, means forming a closure for the upper end of the space between the deflector and extension, said deflector having its lower end open, and means comprising a conduit passing through the cover for directing water through the deflector adjacent the upper end thereof.

In testimony whereof, I affix my signature.

WALTER S. FISHER.
